UNITED STATES PATENT OFFICE.

MAX L. JEFFREY, OF CLEVELAND, OHIO, ASSIGNOR TO THE COLUMBIA AXLE COMPANY, OF CLEVELAND, OHIO, A CORPORATION OF OHIO.

MULTIPLE SPINDLE HEAD.

Application filed December 29, 1919. Serial No. 348,157.

To all whom it may concern:

Be it known that I, MAX L. JEFFREY, a citizen of the United States, and a resident of Cleveland, county of Cuyahoga, and State 5 of Ohio, have invented a new and useful Improvement in Multiple Spindle Heads, of which the following is a specification, the principle of the invention being herein explained and the best mode in which I have 10 contemplated applying that principle, so as to distinguish it from other inventions.

The present invention, relating, as indicated, to a multiple drill head, is directed to an improved mechanism, in which a plurality of drills may be operated from a single shaft or spindle, and which is so constructed as to permit the operation of the several drills at the same speed. A further improvement is the provision of means for 15 varying the operative positions of the drills, both circumferentially of the drill head and radially thereof, in this way adapting the mechanism to many classes of work and permitting almost unlimited adjustment. To 20 the accomplishment of the foregoing and related ends, said invention, then, consists of the means hereinafter fully described and particularly pointed out in the claims.

The annexed drawing and the following 25 description set forth in detail certain mechanism embodying the invention, such disclosed means constituting, however, but one of various mechanical forms in which the principle of the invention may be used.

In said annexed drawing:—

Fig. 1 is a vertical central section partly in elevation of my improved drill head; Fig. 2 is a section on the line 2—2, Fig. 1; Fig. 3 is a section on the line 3—3, Fig. 1; Fig. 4 is a section on the line 4—4, Fig. 1; and Fig. 5 is a bottom plan view of the head.

In Fig. 1 I have shown the driving shaft or spindle 1 of a drill machine housed in a supporting sleeve 2. Fastened to the drill spindle or socket 1 is a driving spindle proper 3, which is attached to a sleeve 4, carrying a main driving gear 5 on its lower end. This driving gear 5 is in mesh with gears 6 mounted on the short shafts 7, one of 45 which also carries a double gear 8, driving gears 9 and 10, of which the former drives a gear 11 mounted on the shaft 12, which is the central drill-receiving shaft of the head, and is in alignment with the axis of 50 the driving spindle 1. The other gear 10 of

the pair of gears 9 and 10 is of the same size as the gear 9 and is mounted on a shaft or spindle 13, which is arranged in a radial position with respect to the central axis of the entire head and is adapted to receive another 60 drill.

There may be a number of shafts or drill-receiving spindles 13 disposed at various points about the central drill spindle 12, there ordinarily being at least two outer 65 drills in addition to the central drill. Such other spindles are similarly driven from the gear 5 through gear 6, shaft 7 and gears 8 and 10.

The supporting sleeve 2 of the drill head 70 is provided with a T-shaped encircling slot 15, in which are movably received the heads 16 of bolts 18 which extend radially outward from socket 2. Carried on the outside 75 of the head or socket 2 are a series of brackets 17 which are mounted in any desired circumferential position by the adjustment of bolts 18. These brackets 17 extend down the outer surface of the socket 2 and are provided with an inwardly extending flange 19, in which are journaled the shafts 7. These 80 shafts 7 are therefore maintained in exactly the same radial position, irrespective of the circumferential position or relation of the brackets 17, and in this way the engagement 85 between the driving gear 5 and the gears 6 on the shafts 7 is also maintained.

Mounted on the lower ends of the brackets 2 are a series of caps 20, in which are carried the lower ends of the various shafts 7, 90 and also the drill members 13. These caps are fastened to the lower surface of the socket by means of bolts 21 and are pivoted about the axis of these bolts, and may be swung inwardly and radially outwardly. 95 When these caps are swung outwardly about the bolt 21 toward the circumference of the head the drill shafts 13 are also carried outward, although they remain in driving engagement with the gears 8, since the arc of movement of the shafts 13 is the common axis of the bolt 21 and the shaft 7 as a center.

The brackets 17 have a circular flange 45 in which the shafts 7 are mounted, while one of the brackets 17 is also provided with an extension 23, which carries the shaft 24, on which the gear 9 is mounted. So long as this bracket is mounted against the side of the head or socket 2 it maintains the shaft 105 110

24 in the same radial position with respect to the central drill 12, and thus provides a continuous and permanent drive from the gear 8 to the gear 11 on the central drill. 5 It will be noticed that the central drill is provided with an upwardly extending end 25 which is journaled in a bushing mounted in the hollow sleeve 4, which is carried in the central spindle of the head.

10 In this construction several drill members may be disposed in any desired relation about the circumference of the head, and may also be adjusted radially by swinging the drill carrying the caps 20 about the bolts 15 21, since this action will swing the drills outward and adjust them with respect to their distance from the center of the entire head. Practically any desired relation of the various drills can be secured in this 20 mechanism and there is the added advantage that all of the drills are driven at exactly the same speed, and there is therefore no lost time as is the case in many of the present drill heads where the central spindle is 25 driven at a speed which is different from that of the outer drills.

Other modes of applying the principle of my invention may be employed instead of the one explained, change being made as 30 regards the mechanism herein disclosed, provided the means stated by any of the following claims or the equivalent of such stated means be employed.

I therefore particularly point out and 35 distinctly claim as my invention:—

1. In a device of the character described, the combination of a head, a centrally mounted driving spindle therein, a central drill rotatably mounted in said driving 40 spindle, a series of brackets movably mount-

ed on said head and adapted to be adjusted circumferentially of said head while remaining at a fixed distance from said central spindle, a drill rotatably mounted on each of said brackets, a circular flange formed centrally of each of said brackets and supporting driving connections for said drills, one of said flanges having an extension, and means carried in said extension for rotating said central drill spindle reversely to said central driving spindle, said connections being operated from said spindle irrespective of the position of said brackets.

2. In a device of the character described, the combination of a head, a centrally mounted driving spindle therein, a transverse opening through said spindle, a tapered axial socket in the base of said spindle communicating with said opening, a tapered sleeve fitted within said socket one end of said sleeve carrying a driving gear and the other end having an extension projecting into said transverse opening, a bushing mounted in the lower end of said sleeve, a central drill rotatably carried in said bushing and driving connections between said driving gear and said rotatable drill spindle.

3. In a device of the character described, the combination of a head, a centrally mounted driving spindle therein, a tapered axial socket in the base of said spindle, a tapered sleeve fitted within said socket, a drill member rotatably carried in said sleeve, a driving gear secured to the free end of said sleeve, and means for transmitting motion from said driving gear to said drill.

Signed by me, this 22 day of December, 1919.

MAX L. JEFFREY.
